UNITED STATES PATENT OFFICE.

STEPHEN P. M. TASKER, OF PHILADELPHIA, PENNSYLVANIA.

IMPROVEMENT IN MANDRELS FOR WELDING TUBES.

Specification forming part of Letters Patent No. **150,374**, dated April 28, 1874; application filed April 4, 1874.

To all whom it may concern:

Be it known that I, STEPHEN P. M. TASKER, of the city and county of Philadelphia, in the State of Pennsylvania, have invented an Improvement in Mandrels and Mandrel-Bars for Manufacturing Metal Tubes, of which the following is a specification:

My invention relates to the construction of the bar with loose mandrels for each pair of rolls when more than one pair of rolls is used in a machine, and when an internal resistance is required against the pressure of the rolls.

In the manufacture of metal tubes, when one pair of rolls is used the mandrel is usually of conical form, and is placed on a pin on the end of the bar; but in using two or more pairs of rolls, the common mode has been to have the mandrels put on the bars as swells, either made fast as part of the bar, or held on by screws or other means, making it difficult to change the mandrels without changing the bar and the mandrels at the same time.

By my improvement I am enabled to change the mandrels as easily as when one pair of rolls is used. To accomplish this purpose I have a shoulder formed on the bar for the inner ball to rest against. This shoulder I usually make by reducing the end of the bar. By this means I maintain its strength, to more effectually resist the great strain against it as a tube is passing over the mandrels. The bar, however, can be made of the reduced size throughout its whole length, by having a collar put on to support the inner mandrel. The outer or end mandrel can be held by the end of the mandrel-bar taking the thrust, or by means of a shoulder. I use, in combination with the mandrels, a connecting-piece, which is a very little smaller in diameter than the mandrels, to avoid friction. This middle piece is intended to sustain the tube as it passes over the mandrels. It is of great advantage in case of a tube sticking on the inner mandrel while the motion is still active on the end mandrel, which has the tendency to make the tube buckle up, making it difficult to remove the mandrel from the tube, and often causing breakage in the machine. The connecting-

piece, being nearly as large as the mandrel, entirely obviates this. As the internal diameter of the tubes vary according to the thickness of the iron, one connecting-piece will answer for a few different sizes of tubes.

In the accompanying drawings, Figures 1, 2, and 3, represent modes of connecting the mandrels B and B' with the mandrel-bar A. Figs. 4 and 5 represent like connections of the mandrels, with the piece C in combination therewith.

Like letters of reference in all the figures indicate the same parts.

A represents the mandrel-bar; B the inner, and B' the outer, mandrel. In Figs. 1 and 4 the main portion of the bar is larger than the end portion, so as to insure great strength to resist the strain upon it as the tube is passing over the mandrels, the end portion A' being reduced to receive the outer mandrel B', and to form a shoulder at a to resist the thrust of the end of the inner mandrel B. The mandrel-bar may, however, be of uniform size throughout its whole length, in which case I form the shoulder a, for the inner mandrel B to rest against, by means of the collar b. (Seen in Figs. 2 and 5.) If desired, the outer part A' of the mandrel-bar may have a shoulder, a', to receive the inner end of the mandrel B', as seen in Fig. 3. The end part A' of the mandrel-bar may be either round, square, or other form.

I have represented the mandrels, as to form, like those in general use; yet any deviation therefrom may be adopted without departing from the principle of my invention.

In Figs. 4 and 5 I have represented a piece, C, on the part A' of the bar, between the inner and outer mandrels B and B'. The object is to prevent the tube being buckled inward by the pressure of the rolls when the tube sticks to the inner mandrel B, which sometimes occurs. To prevent friction on this inner piece as the tubes pass over it, it is made slightly smaller than the mandrels, but large enough to prevent the buckling of the tubes when they stick to the mandrel B. The said middle piece being smaller than the mandrels, and not being rubbed against by the tubes ex-

cept when the sticking occurs, it does not wear out like the mandrels, and, consequently, seldom has to be renewed.

I have only represented two mandrels to a bar, yet it will be seen that any number may be used corresponding to the number of pairs of rolls.

The mandrels B and B', and the piece C, are loose upon the mandrel-bar, so as to drop off for cooling as the bar is withdrawn from the tube.

I claim as my invention—

1. The mandrel-bar A, having a projecting

piece, A', to receive the inner and outer mandrels B and B', and a shoulder, a, to resist the thrust of the inner mandrel B, substantially in the manner and for the purpose described.

2. The combination of the piece C with the part A' of the mandrel-bar, and the mandrels B and B', substantially as and for the purpose set forth.

STEPHEN P. M. TASKER.
